UNITED STATES PATENT OFFICE.

EDWIN P. OSGOOD, OF MALDEN, MASSACHUSETTS.

STORE-SERVICE APPARATUS.

SPECIFICATION forming part of Letters Patent No. 357,851, dated February 15, 1887.

Application filed June 7, 1883. Serial No. 97,376. (No model.)

To all whom it may concern:

Be it known that I, EDWIN P. OSGOOD, of Malden, in the county of Middlesex and State of Massachusetts, have invented a new and 5 useful Improvement in Store-Service Apparatus; and I do hereby declare that the following is a full, clear, and exact description of the same.

My invention is an improved cash-car apparatus or system for sales-rooms and the like.

Heretofore and prior to my invention a cash-carrier has been devised consisting of an elevated wireway with a car mounted on wheels adapted to run upon the way, and provided 15 with an endless cord attached to the car and running over driving-wheels at each end of the way, with means for working the wheels and cord, and thus drawing the car back and forth. Such a cash-carrier is shown in the 20 United States patent to Brown, No. 165,473, granted in 1875.

Also prior to my invention I am aware that loads have been supported on hooks carried on trucks which ran on an elevated way, and 25 were moved by pushing. In such cases, so far as I am aware, the load or the receptacle containing the load was, when moving on the way, attached loosely to the wheel or wheels, so that a push or single impulse would cause 30 the load to swing or oscillate in line with its movement, and this swinging or oscillation, though not greatly objectionable with heavy loads, or when the load was pushed all the way by a continuous or prolonged pushing, is not 35 practicable where a light load is required to be sent by a single impulse from one end of a line of considerable length to the other.

I have found by practical use that a freely-moving car adapted to be thrown by the single impulse of a push from one end of a store to the other, or from the salesman's stand to the cashier's desk, usually a hundred feet and more, is practical, rapid, does not disfigure the store, and does not get out of repair in use. 45 There are no pulleys to provide, put up, or keep in repair, or to disfigure the store; no cord to stretch or break, or rattle of machinery; but to adapt the free movement of a car or carrier to this special service, where the car 50 (which with its load is light) must go the entire length of the way on the momentum of its

original single impulse or push, and where the sender cannot in practice follow it, all rocking or oscillating movement in the line of the impulse must be eliminated. To effect 55 this I have provided for the car two wheels in line with each other and mounted in a suitable frame. This prevents any rocking of the frame longitudinally on the wire or in line with the impulse, and any slight lateral oscillation is not injurious. Further, the car, (or that part on which the hand is placed in impelling the car,) when impelled, must be rigid with the wheel-frame, on which it is supported in the direction of the 65 length of the car or line of movement. If it be attached by a hook, even if there be a two-wheel frame on the car, the load, when started by an impulse of the hand in line with the wire or track, will oscillate in that line, and 70 interferes with the progress of the frame as seriously as if the frame oscillated on one wheel. I therefore attach the car to the frame so that when impelled it will be rigid in the direction of its movement, and when pushed 75 with its load will move as one solid body. As the car is required to go back and forth between the salesman and cashier, it is manifest that the wire must be practically horizontal.

When placed in a store, a cash-car apparatus constructed according to the conditions hereinbefore explained, and substantially as hereinafter explained, may be put up by simply stretching the wire from one end of the store to the other as taut as practicable and 80 without intermediate supports. When so stretched it is scarcely observable, and nothing more is required than to place the car thereon, the car being previously fitted for the purpose, and the store is not obstructed by workmen. 85 The wire fitted to sustain the necessary tension will support the car indefinitely without appreciable wear or liability to disarrangement.

Manifestly the wire and its car may be duplicated or multiplied according to the requirements of the store.

Having thus given a general statement of the conditions and limitations of my invention, I proceed to describe it in detail and with reference to the accompanying drawings, in 90 which—

Figure 1 shows a plan view of the wires

stretched from convenient points in the store and converging to the practical common point at the cashier's desk. Fig. 2 is a side elevation of the car. Fig. 3 shows a section of the car on line $x-x$ of Fig. 2.

In the drawings, a represents the horizontal wires, connected to a fixed support at each end. They are shown as converging from these fixed supports in different parts of the store to the cashier's desk, (indicated at E .) where they are attached to a common bar, A . The bar and other supports must be of sufficient strength to allow the wires to be put under tension, so that they may be held practically horizontal throughout, and so that a car impelled by a push applied by the hand of the operator may pass, by its own momentum, from one end to the other, in either direction. As shown, the ends of the wires are threaded and are strained by means of nuts c . The wires shown are all alike, and each has its appropriate car, so that a detailed description of one answers for all.

The car shown consists of a box, B , which may be of any suitable shape or size under the limitations herein explained. It is suspended beneath the wire on wheels $d d$, running on the wire one behind the other, by means of hangers $e e$, which form a frame for the wheels. The two wheels, one behind the other, prevent any longitudinal oscillation on the axle, to which one wheel would render it liable, and the box or car, being fixed to the hangers, cannot be made to oscillate longitudinally thereon, and moves, with its load, as one rigid body. It is therefore adapted to be impelled from one end of the way to the other in either direction simply by an original impulse given at the start and the untrammelled momentum thereby acquired, and a single impulse being once given the car moves certainly to its destination without further attention from the operator.

A buffer, of india-rubber or some equivalent elastic material, is placed axially upon the wire at or near the end, in order to arrest it with-

out too severe a shock. I prefer to make this stop adjustable by means of a set-screw or other suitable means, whereby it may be set in any desired position.

The wires may be stretched out in an obvious manner, and throughout the store are free from intermediate supports.

I claim as my invention—

1. In a cash-car apparatus, a wire stretched horizontally between fixed supports at each end and in the described relation to the cashier's desk, in combination with a freely-moving car held below the wire on wheel-hangers, to which it is rigidly connected, the wheels thereof being fitted to run one behind the other on the wire, whereby the car is held rigidly against oscillation longitudinally of the way, the whole moving structure being thus adapted to be impelled as a solid body from one end of the way to the other in either direction by the momentum imparted by a single impulse or push, substantially as described.

2. In a cash-car apparatus, a wire stretched horizontally between fixed supports at each end and in the described relation to the cashier's desk, and having adjustable stops placed axially on said wire, in combination with a freely-moving car held below the wire on wheel-hangers, to which it is rigidly connected, the wheels thereof being fitted to run one behind the other on the wire, whereby the car is held rigidly against oscillation longitudinally of the way, the whole moving structure being thus adapted to be impelled as a solid body from one end of the way to the other in either direction by the momentum imparted by a single impulse or push, substantially as described.

In testimony whereof I have signed my name to this specification in the presence of two subscribing witnesses.

EDWIN P. OSGOOD.
